Primary Examiner — Susan E Krakower*(74) Attorney, Agent, or Firm* — Barnes & Thornburg LLP(57) **CLAIM**

The ornamental design for a baby bottle, as shown and described.

DESCRIPTION

FIG. 1 is a perspective of a baby bottle in accordance with my new design;

FIG. 2 is a front elevation view of the baby bottle shown in FIG. 1;

FIG. 3 is a rear elevation view of the baby bottle shown in FIG. 1;

FIG. 4 is a left elevation view of the baby bottle shown in FIG. 1;

FIG. 5 is a right elevation view of the baby bottle shown in FIG. 1;

FIG. 6 is a top view of the baby bottle shown in FIG. 1; and, FIG. 7 is a bottom view of the baby bottle shown in FIG. 1. The broken lines in FIG. 7 illustrate portions of the baby bottle which form no part of the claimed design.
